SHAFT COUPLER

Robert C. Russell, Shaker Heights, Ohio, assignor to Eaton Manufacturing Company, Cleveland, Ohio, a corporation of Ohio

Application May 20, 1955, Serial No. 509,821

4 Claims. (Cl. 268—124)

This invention relates to a shaft coupler and more particularly to a coupler for limiting the transfer of torque from a driving means especially as applied to a window regulating apparatus or the like.

Broadly the present invention comprehends the provision of a bipartite slip coupling member for application to window regulating apparatus and the like interposable between driving and driven rotary members of such apparatus having a coil spring engaging each of the parts thereon so as to "wind up" or be self "energizing" and consequently to facilitate full motor torque transfer in one direction of rotation and to "unwind" or be self "deenergizing" to limit the torque transfer in the other direction of rotation to a proportion of full motor torque. In the latter instance the coil spring of material having a relatively high coefficient of expansion is responsive to heat engendered in slippage of the parts of the coupler under high loads so as to expand radially and consequently to disengage the parts of the coupler or to greatly minimize the torque load acting upon the driving motor.

Many occasions arise wherein it is desirable to provide a coupling for rotative members that limits the maximum torque that may be transferred therethrough for one direction of rotation operation and which provides for the transmission of full torque in an opposite direction. A practical example of such an application is in the coupling between the drive shaft of a motor and the operating mechanism for actuating automatically power operable automotive vehicle windows. It is readily understood that due to human errors, particularly of small children, occasions arise wherein some element, such as a body extremity, may become interposed between the upper extremity of a window and its upper enclosure while the actuating switch for the window is accidentally or inadvertently "turned on" so as to raise the window. Without limiting means in the power circuit of the window actuating apparatus the consequences may be destructive or harmful of either the interposed element or the actuating apparatus. However, with means for limiting the force elevating the window such harmful action may be prevented or greatly alleviated. Accordingly, the present invention is adaptable to the prevention of much difficulty that could arise from objects becoming "stuck" in windows by accomplishing a limiting or removal of the force that the object will be subjected to. In one direction of rotation, as for elevating a window, torque transfer is limited while in the reverse direction full motor torque transfer is effected whereby under conditions of inclement weather, such as the freezing shut of a vehicle window, sufficient power is available to release the window.

It is an object of this invention to provide a shaft coupler that is simple, easy of construction and maintenance and effective for the purpose of transferring varied torques under reverse conditions of operation.

It is a further object of this invention to provide a shaft coupler which provides means for limiting the trans-

2

fer of torque in one direction of rotation to a predetermined proportion of full motor torque while assuring full torque transfer for an opposite direction of rotation.

It is a further object of this invention to provide a shaft coupler that automatically immediately prevents transmission movement of the driven member when the driven member encounters a load in excess of a predetermined slip rating of the coupling and which provides for either a complete disengagement of its driven member from its driving member or a minimization of load upon the driving member after a brief period of operation at overload.

It is a further object of this invention to provide a shaft slip coupler which incorporates means for damping torsional vibrations.

It is a yet further object of the invention to provide a slip shaft coupler as applied to window regulating apparatus for vehicles or the like permitting of limited torque transmission in the closing of a window and providing full torque transmission in an opening operation of the window.

Other and further objects and advantages of this invention will appear from a perusal of the following detailed description taken with the accompanying drawings in which:

Fig. 1 depicts the clutch of this invention as applied to a window operating apparatus,

Fig. 2 is an end view of the clutch shown in Fig. 1,

Fig. 3 depicts the clutch of this invention in a partial sectional view, and

Fig. 4 depicts an end view of the clutch in Fig. 3.

Referring now more particularly to Fig. 1 of the drawing 10 represents a window pane of an automobile or like vehicle which is supported in a sash member 12 extending along the bottom thereof. A sash recess or channel track 14 is provided and is secured to member 12 in some suitable manner as by a pair of angular plates 16. A pair of crossed arms 18 and 20 pivotally secured intermediate the lengths thereof are provided and each has a roller movable along the track 14 attached at its upper end. Arm 18 is pivotal at its other end about a fixed stub shaft pivot 22 and the other end of arm 20 is movable along a fixed track 24 by means of a roller attached to the end of the arm.

Arm 18 is urged in a counterclockwise direction as viewed in Fig. 1 of the drawing by a spirally wound counterbalance spring 26 having one end anchored in a slot in stub shaft 22, fixedly secured to arm 18, and its other end secured to a stationary member forming a part of a fixed bracket 28. The tendency of spring 26 in urging arm 18 in a counterclockwise rotation is to elevate window 10. The torque imparted by spring 26, however, is only sufficient to overcome the force of weight of window 10 and is insufficient to elevate the window of itself.

Bracket 28 provides support for a gear mechanism 31 including a pinion gear 30 which engages a gear sector 32 fixedly secured with arm 18 for rotation therewith about the pivot for shaft 22.

Pinion 30 is driven by a reversible motor 34 having its shaft coupled to a worm gear (not shown) of gear mechanism 31 through the shaft coupler 36. Motor 34 operates to drive pinion 30 and consequently gear sector 32, arms 18 and 20 and window 10 in two directions. In lowering the window 10, coupler 36 provides full torque of motor 36 while in elevating window 10, coupler 36 provides only a fraction of full torque of motor 34; the torque being sufficient to raise window 10 against only moderate resistance. In the event that window 10 encounters large resistance to elevation, coupler 36 pro-

vides slip or relative rotation between its input and output members to alleviate the stress and strain on parts of the window actuator and that affording the resistance to elevation.

Referring now more particularly to Fig. 3 for a more detailed description of the shaft coupler, 38 represents the input shaft to the coupler which may also be the output shaft of motor 34 and 40 represents the output shaft of the coupler. An input member 42 rotatable with shaft 38 is provided having a first reduced cylindrical portion 44 and a second reduced portion 46. An output member including a sleeve element 48 is provided having a reduced cylindrical portion 50 of the same diameter as portion 44 and axially adjacent thereto and with portion 46 telescoped thereby. Reduced portions 44 and 50 taken together provide an annular recess adaptable to receive a coil spring 52 having a portion 43 at one extremity extending axially in a notch in member 42 for driving engagement therewith and with the coiled body thereof extending axially along the recess and wound tightly upon the mentioned reduced portions 44 and 50 in a right hand sense if the worm gear of mechanism 31 has a left hand thread or in a left hand sense if the worm gear is right handedly threaded for a purpose to be described. It is to be understood that in accordance with the invention it is necessary to wind coil spring 52 in a sense so as to tend to unwind as the window is being elevated by the actuators.

Members 42 and 48 are preferably made of cast iron or steel and coil spring 52 of spring bronze although many other materials may also be employed with satisfactory results. In one application of the invention it is paramount that the expansion coefficient of coil 52 be considerably greater than that of member 48. As an example, in one embodiment of the invention member 48 is made of cast iron with a coefficient of expansion equal to .000556 unit per unit length per 100° F. and coil 52 is made of bronze having a coefficient of expansion equal to .000986 unit per unit length per 100° F.

Portion 48 of the output member is attached in some suitable manner to a resilient annular member 54 preferably of synthetic rubber which in turn is attached to an output member 56 rotatable with output shaft 40.

In operation the shaft of motor 34 rotates to initiate operation of the window actuating mechanism. Assuming the coil spring 52 to be wound in a right hand sense and the worm gear of mechanism 31 to be left handedly threaded, a clockwise rotation of the shaft of motor 34 as viewed from the rear and hereinafter referred to as the forward direction is effective to elevate window 10 through the actuating mechanism in a well-known manner. Reverse rotation of motor 34 on the other hand is effective to lower window 10.

In the event that the window mechanism should encounter an unusual resistance to movement as by an obstruction in its path of elevation, coupler 36 is operative to transmit only a fraction of the full torque of motor 34. Spring 52 under the circumstances being frictionally engaged to driven member 48 will tend to unwind and therefore to increase its diameter and consequently to reduce the frictional engagement mentioned. The effect of reduced frictional engagement, of course, is to reduce the torque transferred.

It is readily understood that the above described events result instantaneously to alleviate stresses that may result in the window actuating mechanism as well as to alleviate any harmful forces acting on the obstruction interposed in the path of the window.

In the event that the resistance to elevation of the window should persist and that energization of motor 34 is maintained it is noted that provision is made for further decrease in torque transfer through coupler 36 to alleviate the parts mentioned. Under these circumstances

rotation of member relative to spring 52 is effective to engender considerable heat because of the friction therebetween. Also the heat energy is effective to expand coil 52 considerably more than member 48 by virtue of the different coefficients of expansion of the different compositions thereof to provide a clearance between the engaging members and consequently to further diminish or eliminate the frictional engagement therebetween.

It is also readily understood that upon reverse rotation of motor 15 coil 52 has a tendency to "wind up" on the member 48 so as to increase the frictional engagement therebetween to provide the transfer of full motor torque through coupler 36. As such a sticking of the window in a closed position due to ice or other foreign matter can be overcome and a proper lowering effected.

For the purpose of effecting smooth even performance of the coupler 36 a torsional vibration absorbing member 54 of some suitable resilient material, such as rubber, is provided in the power flow circuit of the coupler. Impulses or vibrations are absorbed therein to reduce the damaging effect thereof on component parts of the actuating mechanism and the window itself.

Another feature of the shaft coupler of the present invention resides in the accommodation thereof to driving and driven shafts that are not in precise axial alignment. Small deviations are "taken up" by spring 52 and resilient member 54 so as to prevent damaging stresses on any of the components of the apparatus.

While the present invention has been described with reference to certain specific embodiments thereof, it is readily apparent to those skilled in the art that it is susceptible to numbers variations and modifications without deviating from the spirit or scope of the invention. It is accordingly intended to cover all such variations and modifications in the appended claims.

What I claim is:

1. A window actuating apparatus comprising means including a first shaft for elevating a window in response to rotation of said shaft in a first direction and for lowering said window in response to rotation of said shaft in a second direction, a reversible motor having an output shaft, a coupler disposed between said first shaft and said output shaft, said coupler comprising a flanged sleeve element fixed to said output shaft, a resilient sleeve having end surfaces and an inside surface, one of said end surfaces and said inside surface being bonded to said flanged sleeve element, a pair of axially adjacent rotatable members, one of said axially adjacent rotatable members being bonded to the other end surface of said resilient sleeve and the other of said axially adjacent rotatable members being fixed to said output shaft, said rotatable members having axially adjacent, radially reduced portions of equal diameter to form an axially extending annular recess, a coil spring located in said recess in frictional engagement with each of said members and having driving engagement with one of said members, said coil spring being of different composition from that of at least one of said members and having a coefficient of expansion greater than the coefficient of expansion of at least one of said members of different composition thereto, and said coil spring being wound so as to advance when rotated in said first direction whereby torque transferred by said coupler is reduced in response to resistance to elevation of said window.

2. A window actuating apparatus according to claim 1 wherein the coefficient of expansion of said spring is greater than that of said members.

3. A window actuating apparatus according to claim 1 wherein the spring is secured to one of said members and wherein said spring is operative to transmit full motor torque for a lowering of window.

4. A shaft coupler according to claim 3 wherein the composition of one of said member along the por-

tions in contact with said spring is cast iron and the composition of said spring is bronze.
